[57] CLAIM

The ornamental design for a game target or similar article, substantially as shown and described.

DESCRIPTION

FIG. 1 is a front elevational view of a game target showing my new design, it being understood that the hatching in the compartments is uniform throughout but shown fragmentarily for convenience of illustration; FIG. 2 is a right side elevational view.

FIG. 3 is a top plan view of FIG. 2; and

FIG. 4 is a bottom plan view of FIG. 2 but without the numerical indicia in FIG. 1.
